UNITED STATES PATENT OFFICE.

JEROME B. REED, OF SUNBURY, PENNSYLVANIA.

ROASTER AND BAKER.

SPECIFICATION forming part of Letters Patent No. 268,532, dated December 5, 1882.

Application filed July 1, 1882. (No model.)

To all whom it may concern:

Be it known that I, JEROME B. REED, a citizen of the United States, residing at Sunbury, in the county of Northumberland and State of Pennsylvania, have invented certain new and useful Improvements in Roasters and Bakers, of which the following is a specification, reference being had therein to the accompanying drawings.

10 The object of my invention is to provide a roaster and baker which may be utilized upon the tops of cooking-stoves and ranges, and in which the articles being cooked will be automatically basted.

15 The invention consists in certain novel features of construction, which will be hereinafter fully described, and pointed out in the claims.

In the drawings, Figure 1 is a front end elevation of the roaster and baker with its door closed. Fig. 2 is a similar view with the door removed. Fig. 3 is a vertical longitudinal section, the door being shown as partially open.

The letter A indicates a rectangular oblong box, formed of sheet metal, preferably sheet iron or tin. It is supported upon legs b, formed by extending its side walls below its bottom, the lower edges of these walls being notched to allow a free circulation of hot air under the bottom of the box when in use.

30 Along the longitudinal center of the top plate, a, of the box and on the under side of said plate, is a cold-air conduit, D, the top wall of which is formed by a portion of the plate, a, and the downwardly-converging walls d d of which are formed by a properly-bent plate of sheet metal. The meeting edges of these walls d d form a sharp angle directly over the center of the bottom of the box, and the conduit D is open at both ends, its rear end opening through the rear end wall of the box, and the door E being provided with a triangular opening, e, which coincides with the open front end of the conduit in order to permit free passage of air to and from the conduit when the door is closed, as shown in Fig. 1. The office of the conduit D is to permit a free circulation of cold air, which will keep the converging walls d d cool, so that they will to a great extent condense the steam coming in contact

45 with them from the articles roasting in the pan F on the bottom of the box. As this steam is condensed the water of condensation flows

down the inclined walls and trickles off the angle formed by said walls, falling upon the roasting articles in the pan, thus automatically basting said articles with water impregnated with the flavor of the same, and rendering unnecessary the opening of the box for basting.

55 The door E is provided with flanges e' e' at its vertical edges to strengthen it, and through which are passed the hinge pins or pivots g g, by which it is secured to the side walls of the box, the door closing between said walls and against flanges h h, which extend down to the lower edges of the walls below the bottom of the box. The flanges e' e' are extended outward at their lower ends to form lugs i i, which will strike the flanges h h and support the door in a horizontal position, when it may be used to support the pan, which may be drawn out upon it when it is desired to remove or turn the articles cooking. The flanges e' e' h h and the lugs i i may be strengthened, if desired, by forming them of double thickness or two layers of metal.

75 The letter L designates a sliding plate, moving in guides on the door, and arranged to cover an opening therein. When the box is used as a baker this slide is to be drawn back to uncover the opening and permit the escape of steam, which will then not be condensed, nor fall back in the shape of water upon the bread, cakes, pies, or similar articles, which do not require to be basted.

80 In order to avoid the frequent opening of the door and consequent interruption of the process of cooking, I provide said door with a mica window, M, through which the articles in the pan may be inspected.

85 When the box is made mainly of tin the bottom and lower portions of the side walls, forming the legs, may be made of sheet-iron.

Having now fully described my invention, what I claim is—

1. The roaster and baker consisting of the sheet-metal box having in its upper portion the cold-air conduit, substantially as described, and for the purpose set forth.

2. The combination, with the sheet-metal box having in its upper portion the cold-air conduit open at both ends, of the door having the opening coinciding with said conduit when the door is closed, substantially as described.

3. The sheet-metal box A, supported on

suitable legs and having the cold-air conduit
D, inclosed partially by the top plate of the
box and partially by the converging walls d d,
which meet at an angle over the bottom of
the box, said conduit being open to access of
cold air from without the box, substantially as
described.

In testimony whereof I affix my signature in
presence of two witnesses.

JEROME B. REED.
